UNITED STATES PATENT OFFICE.

ARTHUR B. WARING, OF YONKERS, NEW YORK.

MACHINE FOR FORMING NAPPED BATS FOR HAT-BODIES.

SPECIFICATION forming part of Letters Patent No. 732,475, dated June 30, 1903.

Application filed March 12, 1902. Serial No. 97,832. (No model.)

To all whom it may concern:

Be it known that I, ARTHUR B. WARING, a citizen of the United States of America, and a resident of Yonkers, in the county of West-
5 chester and State of New York, have invented certain new and useful Improvements in Machines for Forming Napped Bats for Hat-Bodies, of which the following is a specification.

10 This invention relates to machines for forming napped bats for hat-bodies by which a nap is formed and is so confined that a felted article or hat-body may be applied thereto for the eventual purpose of producing a hat with a napped surface. In forming-machines of this class heretofore in use the trunk through which the fibrous material is sucked onto the "cone" or disk to receive the nap was stationary and the cone or
15 disk had to be removed before the felted body could be placed on the nap, the consequence of which was that the shifting of the nap resulted in an objectionable disarrangement of the fibers or a breaking of the same.

20 The main object of the present invention is to provide a forming-machine in which the shifting of the nap for the placing of the felted body thereupon is avoided. This is accomplished by the provision of a movable trunk, which permits the felted article or
25 hat-body to be placed upon the nap before the cone or disk is removed from the holder of the former. While the hat-body is being placed upon the nap, the nap is held in place
30 without disarrangement by the suction through the perforated cone or disk.

35 Further objects of the invention are to provide a forming-machine in which the trunk is so constructed as that it will accommodate itself to the edges of cones or disks of various diameters against which the trunk may be set, also to provide a practically air-tight joint at the meeting edges of the trunk and the cone or disk, thereby preventing an unequal distribution of the fibrous material on the cone, which would result if there were any chance for the exterior air to be sucked in through a crack or space between the adjacent edges of the trunk and cone or disk.

40 45 50 With this end in view my invention consists in certain features of construction and

combinations of parts to be hereinafter described and then pointed out in the claims.

In the accompanying two sheets of drawings, Figure 1 is a side elevation of a machine 55 for forming napped bats in accordance with my invention. Fig. 2 is a plan view of the same. Fig. 3 is a longitudinal section of the main parts of the machine enlarged, showing the same in using position. Fig. 4 is a 60 similar section showing the distributing-trunk moved away from the holder of the forming-machine, so that the perforated cone or disk may be lifted out after the felted article or hat-body has been applied to the nap. 65 Fig. 5 is a plan view of the perforated cone or disk. Fig. 6 is a side elevation of the same. Fig. 7 is a transverse section of the perforated cone or disk. Figs. 8 and 9 are 70 edge and plan views of the holder for the disk, and Fig. 10 is a sectional detail showing a modification.

Referring to the drawings, the main frame 1 of the machine is of suitable construction and carries, as usual, guide-rollers 2 for an 75 endless apron 3, at the delivery end of which is a pair of feed-rollers 4 for feeding the fibrous material which is placed upon the apron 3 to a picker-cylinder 5 in the well-known manner. The picker-cylinder 5 is provided 80 with a shaft 6, journaled in suitable bearings of the main frame 1, and is provided with a pulley 7, so that the picker may be driven at a rapid rate from a suitable power-transmitting mechanism, which is adapted to in turn 85 impart a slow speed to the traveling apron 3 and also to the perforated cone or disk 8, to be hereinafter described. The details of the power-driven mechanism are not essential, as any suitable form of mechanism may be 90 resorted to.

The picker-cylinder 5 is housed within a stationary casing 9, suitably supported on the main frame 1 and provided with an opening 10, in which the feed-rollers 4 are located. 95 Mounted on the opposite open portion of the casing is a movable trunk 11, preferably elbow-shaped and formed of sheet metal, and the adjacent edges of which trunk and casing correspond and fit together practically 100 air-tight. The connection between the casing and the trunk is formed by means of a

5 pivot-pin 12, which passes through suitable ears or lugs 13 14 on the casing and trunk, respectively, so that a hinge connection for the trunk is provided, thereby permitting the 10 trunk to be swung or adjusted by suitable means. This means, in the present instance, consists, preferably, of a suitable treadle 15, adapted to exert a pull upon a rope 16, attached to and trained over a segmental pulley 17, which is mounted on a rock-shaft 18, journaled in suitable bearings 19 and supporting a pulley 20, over which is trained a rope 21, connected on the one hand with a suitable eye 22 on the back of the trunk and 15 carrying a counterweight 23. By this means the trunk may be lifted by pressing upon the treadle, and when the pressure is released the trunk will settle gently back to position, due to the restraining tendency of the counter-weight 23. Of course the invention is not necessarily limited to a trunk movable perpendicularly, as it is within the power of skilled mechanics to construct it to move in any direction, as sidewise, without avoiding 20 the scope and spirit of the invention.

25 The mouth of the trunk is adapted to center over a suction-chest 24, on the top of which revolves the turn-table 25, on which rests the disk-holder 26 of the former. The 30 turn-table 25 has a series of peripheral teeth 25^a intermeshed by a suitably-operated driving-gear 27. An eduction-pipe 28, leading to a suitable exhaust or suction fan, (not shown,) leads from the suction-chest 24, so that suction 35 may be exerted on the perforated cone or disk which may be placed in the holder 26.

40 The perforated cone or disk 8 (shown more particularly in Figs. 5, 6, and 7) consists of an interstitial plate formed by a perforated plate or a wire screen 29, which is reinforced, strengthened, and retained in an annular rim 30, which consists, preferably, of an upper and a lower section between which the 45 said screen, to be hereinafter designated the cone or disk "bottom," is placed. The cone or disk so formed is equipped with diametrical handles or grips 31, whereby the same may be lowered into the holder of the forming-machine or lifted out of the same. While 50 the cone or disk bottom is preferably flat, as shown, the word "cone" is used throughout this specification for the reason that it has a distinct meaning in the art.

55 The described or equivalent means for moving the mouth of the trunk 11 from the edge of the perforated cone or disk with which it is approximately concentric enables the advantage previously stated to be accomplished—that is, the possibility of placing 60 the felted body upon the nap while said nap is held in its position by suction upon the perforated cone or disk.

65 Perforated cones or disks of different diameters may be set in the holder of the forming-machine, and one object of the invention is to practically, if not absolutely, form an air-tight joint between the mouth of the

trunk and the adjacent edge of the cone. This may be accomplished by flaring the mouthpiece 32 of the trunk, so that when the 70 trunk is lowered various diameters of cones or disks may snugly fit into it. An alternative construction is shown in Fig. 10, wherein the flare is shown upon the cone or disk, the end of the trunk being without flare. 75

By reason of the fact that the mouthpiece is movable and that it has a flare it may be said to be adjustable to various diameters of cones or disks, for when the mouthpiece is fitted to a cone or disk of one diameter the 80 zone of contact will be of a corresponding diameter, and when a cone or disk of a smaller diameter is substituted the zone of contact will not be the same, but will be of corresponding diameter. So, also, if a cone or disk 85 of larger diameter is substituted for one of smaller diameter the zone of contact will not be the same, but will be of corresponding larger diameter. If the mouthpiece were not movable, this adjustment could not be obtained unless the cone or disk were moved 90 toward it. My invention is not, however, restricted to the specific means shown for accomplishing the purpose in view of forming a joint with the cones or disks. 95

The flaring mouthpiece 32 is self-adjusting, this being permitted by the provision of a flexible throat 33, which consists of a band or ring of flexible material—such as canvas, rubber, leather, or other suitable yielding or flexible material—which is connected to the main body of the trunk and the mouthpiece by riveting or the like. A distinct advantage is gained by this flexible throat in the trunk in that the mouthpiece 32 of the trunk 105 will more readily form a practically air-tight joint with the adjacent edge of the perforated cone or disk than were such a flexible throat omitted; but the invention is not restricted to the use of the flexible throat. A perfect 110 joint between the mouthpiece of the trunk and the perforated cone or disk is most desirable for the reason that if there be any crack or air-space between the portions which meet or should meet an unequal distribution 115 of the fibrous material on the bottom of the cone or disk results, due to the fact that the outer air is sucked in through the crack or space, causing a thinning of the periphery or outer portion of the nap. In a perfect 120 machine the suction should not draw any outer air into the trunk or cone excepting through the casing 9.

When the machine is in operation, the picker breaks up the fibrous material fed to 125 it and discharges the same into the trunk 11, and the suction acting upon the fibers thrown toward the perforated cone or disk 8 by the picker causes the fibers in the trunk to be evenly distributed over the bottom of the 130 cone or disk, and this is largely due to the fact that the cone or disk is mounted in a plane approximately parallel with the plane of the delivery-mouth of the trunk, so that

at one time during the delivery of the fibrous material the whole perforated or interstitial surface of the cone or disk may be exposed to the delivery-mouth of the trunk. The nap 5 so formed may immediately receive the felted article or hat-body just as soon as the trunk is moved away from the cone. The nap and felted article or hat-body may then be removed, so as to undergo the act of sticking them together in any suitable manner.

What I claim as new and of my invention is—

1. In a machine for forming napped bats for hat-bodies, the combination of a movable 15 trunk for delivering the fibrous material, and a perforated cone or disk, the whole perforated surface of which is exposed, at one time, during delivery of the fibrous material, to the delivery-mouth of the trunk, substantially as 20 described.

2. In a machine for forming napped bats for hat-bodies, the combination of a movable trunk for delivering the fibrous material, and a perforated cone or disk, mounted in a plane 25 approximately parallel with the plane of the delivery-mouth of the trunk, substantially as described.

3. In a machine for forming napped bats for hat-bodies, the combination of a stationary supporting-casing, a picker inclosed in 30 the same, a curved trunk with a laterally-directed delivery-mouth, the trunk being movably mounted on the casing, and a perforated cone or disk opposite the delivery-mouth of 35 the trunk, substantially as described.

4. In a machine for forming napped bats for hat-bodies, the combination of a stationary supporting-casing, a picker inclosed in the same, a curved trunk with a laterally-directed 40 delivery-mouth, the trunk being movably mounted on the casing, and a perforated cone or disk, the whole perforated surface of which is exposed, during operation, to the delivery-mouth of the trunk, substantially as described.

5. In a machine for forming napped bats for hat-bodies, the combination of a stationary supporting-casing, a picker inclosed in the casing, a trunk with a laterally-directed 50 delivery-mouth, the trunk being movably mounted on the casing, and a rotary perforated cone or disk, turning in a plane approximately parallel with the plane of the delivery-mouth of the trunk, substantially as described.

6. In a machine for forming napped bats for hat-bodies, the combination of a casing, a picker therein, a trunk movable relatively to the casing and provided with a laterally-directed delivery-mouth, and a perforated cone or disk opposite the mouth, substantially as described.

7. In a machine for forming napped bats for hat-bodies, the combination of a casing, 60 a picker, a trunk hinged at its upper side to the casing, and a perforated cone or disk lo-

cated below the delivery-mouth of the trunk, substantially as described.

8. In a machine for forming napped bats for hat-bodies, the combination of a support, 70 a perforated cone or disk, and a movable delivery-trunk, mounted on the support, curved toward and closing on the cone or disk, substantially as described.

9. In a machine for forming napped bats 75 for hat-bodies, the combination of an open casing, a perforated cone or disk located to one side of the opening through the casing, and a trunk movable on the casing and having a delivery-mouth directed laterally toward and closing on the cone or disk, substantially as described.

10. In a machine for forming napped bats for hat-bodies, the combination of a perforated cone or disk, and a movable trunk 80 directed toward and closing on it, substantially as described.

11. In a machine for forming napped bats for hat-bodies, the combination of a perforated cone or disk, and a movable trunk 90 directed toward and closing on it, one of said parts of the machine having a flare at the meeting edges, substantially as described.

12. In a machine for forming napped bats for hat-bodies, the combination of a perforated cone or disk, and a movable trunk 95 provided with an outwardly-flaring mouthpiece, substantially as described.

13. In a machine for forming napped bats for hat-bodies, the combination of a perforated cone or disk, and a trunk provided with 100 a mouthpiece opposite the cone or disk and adjustable to various diameters of cones or disks, substantially as described.

14. In a machine for forming napped bats 105 for hat-bodies, the combination of a perforated cone or disk, and a trunk provided with a self-adjusting mouthpiece directed toward the cone or disk, substantially as described.

15. In a machine for forming napped bats 110 for hat-bodies, the combination of a perforated cone or disk, a movable trunk, and a self-adjusting mouthpiece for said trunk, directed toward the cone or disk, substantially as described.

16. In a machine for forming napped bats for hat-bodies, the combination of a trunk, a mouthpiece therefor, a flexible throat connecting the trunk and the mouthpiece, and a perforated cone or disk opposite the mouthpiece and upon which the mouthpiece seats, substantially as described.

17. In a machine for forming napped bats for hat-bodies, the combination of a trunk, a flaring mouthpiece therefor, a flexible throat 125 connecting the trunk and the mouthpiece, and a perforated cone or disk opposite the mouthpiece, substantially as described.

18. In a machine for forming napped bats for hat-bodies, the combination of a trunk 130 for delivering fibrous material, a perforated cone or disk, and means forming a closed

joint directly between the trunk and cone or disk, substantially as described.

19. In a machine for forming napped bats for hat-bodies, the combination of a suction-chest, a rotary disk-holder, a perforated cone or disk on the same, and a movable trunk, the delivery-mouth of which closes on the cone or disk, substantially as described.

20. In a machine for forming napped bats for hat-bodies, the combination of a suction-chest, a perforated cone or disk on the same, and a movable trunk having a yielding mouth-piece which closes on the cone or disk, substantially as described.

21. In a machine for forming napped bats for hat-bodies, the combination of a suction-chest, a perforated cone or disk on the same,

and a movable trunk, the delivery-mouth of which fits against the cone or disk, the trunk being arranged over the suction-chest and movable away from it, substantially as described.

22. In a machine for forming napped bats for hat-bodies, the combination of a movable trunk, and a perforated cone or disk concentric with the delivery-mouth thereof, substantially as described.

Signed at Yonkers, New York, this 8th day of March, 1902.

ARTHUR B. WARING.
